(57) **CLAIM**

The ornamental design for a rocker switch for a remote control, as shown and described.

DESCRIPTION

FIG. 1 is a left, top perspective view of our design of a rocker switch for a remote control.

FIG. 2 is a right, top perspective view thereof.

FIG. 3 is a top plan view thereof.

FIG. 4 is a bottom view thereof.

FIG. 5 is a left, side elevation view thereof.

FIG. 6 is a right, side elevation view thereof.

FIG. 7 is a front elevation view thereof; and,

FIG. 8 is a rear elevation view thereof.

The broken lines shown in the figures represent portions of the rocker switch for remote control and form no part of the claimed design.
